UNITED STATES PATENT OFFICE.

NELSON W. PERRY, OF CINCINNATI, OHIO, ASSIGNOR OF ONE-FOURTH TO
THOMAS T. GAFF, OF SAME PLACE.

ELECTRIC-DISTRIBUTION SYSTEM FOR RAILWAYS.

SPECIFICATION forming part of Letters Patent No. 496,533, dated May 2, 1893.

Application filed May 27, 1891. Serial No. 394,259. (No model.)

To all whom it may concern:

Be it known that I, NELSON W. PERRY, a citizen of the United States, residing at Cincinnati, in the county of Hamilton and State 5 of Ohio, have invented certain new and useful Improvements in Systems of Electric Distribution and in Mechanism Therefor, of which the following is a specification.

My invention relates more particularly to 10 methods of electric distribution for moving translating devices operated by the multiple arc system. In the systems of electric distribution for moving translating devices now in use the liability to leakage and the danger incident to the use of bare working conductors 15 has been a serious drawback both in overhead and underground systems but especially in the latter.

It is the object of my invention to provide 20 a system of distribution in which the danger and the liability of leakage from the working wires will be reduced to the minimum and the invention consists in the system and the mechanism hereinafter described.

25 In the drawings: Figures 1, 2 and 3 are dia-
grammatic views showing my invention applied to an electric railway operated by a single working conductor, or trolley wire, the motor being shown in different positions in 30 each of the figures. Fig. 4 is a like view showing my invention applied to a double trolley line. Fig. 5 is a detail of a portion of a trip switch.

A is the outgoing or positive feed wire and 35 A' (Fig. 4) a return or negative feed wire em-
ployed in roads operated on the double trolley system.

B, B² and B⁴ represent sections of the work-
ing conductor, each section lapping but nor- 40 mally insulated from the adjacent sections.

B', B³ and B⁵ (Fig. 4) represent sections of 45 a second working conductor used in the dou-
ble trolley system.

The feed wire A is connected with section 50 B of the working conductor by branch feed
wires a c and c b, normally disconnected, but
adapted to be connected by a switch, or cir-
cuit breaker, C, with section B' by wires a' c'
and c' b' adapted to be connected by a switch
C', &c.

D, D' are supplemental conductors adja-

cent to the lapping portions of the working conductor but normally insulated therefrom. D is connected with D' by a wire d d', D² with D³ by a wire d² d³, &c.

E E' are solenoid magnets connected re-
spectively with the wires d d', d² d³, &c., by 55 wires e d, e' d, &c. The armatures e of these magnets carry hook shaped extensions e', preferably pivotally attached thereto and 60 adapted to take about levers F. The levers F are fulcrumed at f and provided near the fulcrum point with V-shaped lugs or projec-
tions f'. They are also provided with weights f² adapted to bring the center of gravity of 65 the lever above the point of support.

The levers are adapted to actuate the cir-
cuit breaking devices C C', &c., in the con-
nections a c c b, &c., between the main con-
veyer and the sections of the working con-
ductor I have illustrated these circuit break-
ing devices as consisting of yokes or forks C 70 C', &c., adapted to take into pairs of mercury
cups c c, c' c', &c., one member of each pair
being mounted at the adjacent ends of the 75 wires a c and c b, a c', c' b', &c., and a space
being left between the cups. The solenoids
E E' are connected with the return. In the
single trolley system the ground is used for
the return and the connection from the solenoids 80 is by wires g, g', g², &c. When the double
trolley system is used, the return wire, A', is
connected with the negative trolley wire (as
shown in Fig. 4) by wires a' c⁴ and c⁴ b', nor-
mally disconnected by a switch or circuit 85 breaker C⁴. It will be understood that the
return wire is connected in the same manner
with each section of the trolley wire. The cir-
cuit breaker C⁴ is preferably actuated by the
same magnet which actuates its companion 90

circuit breaker C and for that purpose the lever
F carries a bar f³ to which are attached the
circuit breaker C and C⁴. In the double trolley
system the return being metallic the solenoids 95 E, E', &c., are connected with the re-
turn wire by a wire e a' instead of with the
ground as in the single trolley system.

In Fig. 1 the motor M is represented as in
electrical connection with one section of the
working conductor of a single trolley line. 100
In Fig. 2 the motor is represented as approach-
ing another section of the working conductor,

the switch in the branch feed wire which applies current to the section about to be reached having been closed.

In Fig. 3 the motor is represented as in electrical connection with the lapping portion of two adjacent sections of the working conductor, the circuit through the branch feed wire which supplies current to the first of the two having been broken. The operation when the motor is in electrical connection with a section of the working conductor and the switch wire which supplies that section closed requires no explanation. The switch in the branch feed wire supporting the next succeeding section should be open. When the trolley, or other current gathering device, contacts with supplemental conductor D^2 , a current is established through $d^2 d^3, e^2 d$, magnet E' and the ground connection g' . This current vitalizes the magnet E and actuates its armature lifting the free end of the lever F' and lowering the fork C' into the mercury cups c' thereby making electrical connection between the main feed wire A and section B^2 of the working conductor. As the motor proceeds the trolley contacts with the supplemental conductor D^2 and a current is established through $d^2 d^3, e^2 d$, magnet E and the ground connection g . This current vitalizes magnet E and actuates its armature thereby reversing the position of lever F and breaking the connection in the branch feed wire $a c, c b$. This cuts section B of the working conductor out of circuit. As soon as the trolley passes from its contact with one of the supplemental conductors the current through the magnet is broken and the armature drops thereby lowering the lever-actuating hook but, the center of gravity of the lever being above its fulcrum, the lever will retain its position until positively actuated. When the lever is tilted the point of its V -shaped projection will extend beyond the normal position of the lever-actuating hook and when the latter drops it always assumes a position under the opposite face of the V -shaped projection from that upon which it last acted. The result is that, each time a magnet is vitalized, the position of the lever which it controls is reversed and the lever retains its position until the magnet is again vitalized. The supplemental wires are so arranged that as the motor approaches a lap between sections of the working conductor the supplemental conductor, connecting with the switch controlling the section ahead, is first embraced, then the working conductor of the succeeding section, then, and before passing from either of the other three wires, the supplemental conductor connecting with the switch controlling the section the car is leaving.

I claim—

1. The combination, in a system of electric distribution for moving translating devices, of a feed wire; a supplemental working conductor; branch feed wires, normally broken, leading from the main feed wire to the sec-

tions of the working conductor, supplemental conductors adjacent to the ends of the sections of the working conductor; a magnet for each section of the working conductor; a connection from the supplemental conductors at each end of a section of the working conductor, through a magnet, to the return; a lever provided with a V -shaped projection, and carrying at one end a circuit breaking and closing device adapted to close the break in the branch feed wire connected with that section; a hook-shaped extension carried by the armature of the magnet and adapted to take under the V -shaped projection, substantially as and for the purpose specified. 70 75 80

2. The combination, in a system of electric distribution for moving translating devices, of a feed wire; a supplemental working conductor each section lapping but normally insulated from the adjacent sections; branch feed wires, normally broken, leading from the main feed wire to the sections of the working conductor, supplemental conductors adjacent to the ends of the sections of the working conductor; a magnet for each section of the working conductor; a connection from the supplemental conductors at each end of a section of the working conductor, through a magnet, to the return, a lever provided with a V -shaped projection and carrying at one end a circuit breaking and closing device adapted to close the break in the branch feed wire connected with that section; a hook-shaped extension carried by the armature of the magnet and adapted to take under the V -shaped projection, substantially as and for the purpose specified. 85 90 95

3. The combination, in a system of electric distribution for moving translating devices, of a feed wire; a supplemental working conductor; branch feed wires, normally broken, leading from the main feed wire to the sections of the working conductor; supplemental conductors adjacent to the ends of the sections of the working conductor; a magnet for each section of the working conductor; a connection from the supplemental conductors at each end of a section of the working conductor, through a magnet, to the return, a weighted lever, provided with a V -shaped projection, and carrying at one end a circuit breaking and closing device adapted to close the break in the branch feed wire connected with that section; a hook-shaped extension carried by the armature of the magnet and adapted to take under the V -shaped projection, substantially as and for the purpose specified. 105 110 115 120 125

4. The combination, in a system of electric distribution for moving translating devices, of a feed wire; a sectional working conductor; branch feed wires, normally broken, leading from the feed wire to the sections of the working conductor; mercury cups at the disconnected ends of the branch feed wires; supplemental conductors adjacent to the ends of the sections of the working conductor; a mag- 130

net for each supplemental conductor; a connection from the supplemental conductors at each end of a section of the working conductor, through the magnet, to the return; a lever provided with a V-shaped projection and carrying a fork adapted to take into the mercury cups on the branch feed wire; a hook-shaped extension carried by the armature to the magnet and adapted to take under the V-shaped projection, substantially as and for the purpose specified.

5. The combination, in a system of electric distribution for moving translating devices, of a feed wire; a sectional working conductor; branch feed wires, normally broken, leading from the feed wire to the sections of the working conductor, mercury cups at the disconnected ends of the branch feed wires; supplemental conductors adjacent to the ends of 15 the sections of the working conductor; a magnet for each supplemental conductor; a connection from the supplemental conductors at each end of a section of the working conductor, through the magnet, to the return; a lever provided with a V-shaped projection and carrying a fork adapted to take into the mercury cups on the branch feed wire; a hook shaped extension pivoted to the armature of the magnet and adapted to take under the V-shaped 20 projection, substantially as and for the purpose specified.

6. The combination in a system of electric distribution for moving translating devices of an outgoing feed wire, an incoming feed 35 wire; two sectional working conductors; branch feed wires normally broken connecting the outgoing feed wire with the sections of one of the working conductors, and the incoming feed wires with the sections of the other working conductor; switches adapted to close the breaks in the branch feed wires; magnets controlling the switches; supplemental conductors adjacent to each end of the sections of the working conductors and a 40 connection from the supplemental conductors at the ends of a section of the working conductor through the switch controlling magnet

to the return, substantially as and for the purpose specified.

7. The combination in a system of electric 50 distribution for moving translating devices of an outgoing feed wire, an incoming feed wire, two sectional working conductors, lapping but normally insulated from each other; branch feed wires normally broken, connecting 55 the outgoing feed wire with the sections of one of the working conductors, and the incoming feed wires with the sections of the other working conductor; switches adapted to close the breaks in the branch feed wires; 60 magnets controlling the switches; supplemental conductors adjacent to each end of the sections of the working conductors and a connection from the supplemental conductors at the ends of a section of the working conductor through the switch controlling magnet 65 to the return, substantially as and for the purpose specified.

8. The combination in a system of electric distribution for movable translating devices 70 of the feed wire A; the sectional working conductor B B²; the branch feed wires a c and and c b; the supplemental conductors D, D'; the magnet E; the connections d d', e d; the hooked extension e' carried by the armature 75 of the magnet and the lever F carrying the switch C, substantially as and for the purpose specified.

9. The combination in a system of electric distribution for moving translating devices 80 of the outgoing feed wire A, the incoming feed wire A'; the sectional working conductors B B² and B' B³; the branch feed wires a c and c b, a' c⁴; the supplemental conductors D D'; the magnet E; the connections d d', e d and 85 e a'; the hooked extension e' carried by the armature of the magnet and the lever F carrying the switches C and C⁴, substantially as and for the purpose specified.
